UNITED STATES PATENT OFFICE.

LAURENCE J. BERKELEY, OF RACINE, WISCONSIN, ASSIGNOR TO WALKER MANUFACTURING COMPANY, OF RACINE, WISCONSIN, A CORPORATION OF WISCONSIN.

LIFTING-JACK.

1,333,239.

Specification of Letters Patent.

Patented Mar. 9, 1920.

Application filed June 14, 1919. Serial No. 304,198.

To all whom it may concern:

- Be it known that I, LAURENCE J. BERKELEY, a citizen of the United States, residing at Racine, in the county of Racine and 5 State of Wisconsin, have invented certain new and useful Improvements in Lifting-Jacks, of which the following is a specification, reference being had to the accompanying drawing, forming a part thereof.
- 10 The main objects of this invention are to produce a lifting jack which can be conveniently operated at a distance from and clear of the load which it lifts and the operating connections of which can be readily 15 shifted out of the way, as for example, for working on the load, such as an automobile or other vehicle, while supported by the jack; and generally to improve the construction and operation of devices of this class.
- 20 It consists in the construction, arrangement and combination of parts as herein-after particularly described and pointed out in the claims.

In the accompanying drawing like characters designate the same parts in the several figures.

Figure 1 is a side elevation of a lifting jack embodying the invention, showing the lifting member raised and the hand operating lever extended and turned down and locked for holding the lifting member and its load in an elevated position; Fig. 2 is a plan view of the jack showing the parts in positions corresponding with those shown 35 in Fig. 1; Fig. 3 is a reverse side elevation of the jack showing the lifting member lowered and the hand operating lever folded down thereon; Fig. 4 is a vertical cross section on the line 4—4, Fig. 3; and Figs. 5, 40 6 and 7 are detail views on an enlarged scale showing the flexible thrust member and associated parts of the jack, Fig. 5 being a vertical longitudinal section on the line 5—5, Figs. 6 and 7, Fig. 6 a cross section on the line 6—6, Fig. 5, and Fig. 7 a horizontal section on the line 7—7, Fig. 3.

The frame or body of the jack comprises a hollow upright post or standard 1, which is formed or provided adjacent its lower 45 end with a horizontal or lateral extension 2, and serves to firmly support the standard 1 in operative position and to carry in a conveniently accessible position the levers for operating the lifting member of the jack.

The jack may be, and is preferably,

mounted on wheels, to facilitate its transfer from place to place and to shift the position of the extension 2 and operating levers so as to carry them out of the way when a load, such as an automobile or other vehicle, is 60 supported on the jack. To this end a pair of truck wheels 4, are mounted on the ends of a transverse axle 5, carried by a bracket 6, which may be cast as shown, on the front side of the standard 1 adjacent its lower 65 end. At its opposite or rear end, the extension 2, which is preferably curved upwardly as shown in Figs. 1 and 3, is supported on a caster wheel 8, the frame 9 of which is swiveled in a hub 10 formed with 70 the extension 2, ball or roller thrust bearings being preferably provided between the hub and caster frame, as shown in Fig. 4.

The standard 1 is formed with a vertical guideway in which a sleeve 12 is fitted. A 75 lifting member, which may consist as shown, of a ratchet bar 14, provided at its upper end with a swivel plate or bearing 15, is slidably fitted and movable vertically in the sleeve 12, or with the sleeve in the stand- 80 ard 1.

An elbow-shaped guide conduit 17 is formed in the standard 1 and extension 2, the vertical portion of the conduit in the standard being parallel with and opening 85 into the guideway for the sleeve 12 and ratchet bar 14.

The sleeve 12 is formed or provided with a lug 19, which projects into and is adapted to traverse the vertical part of the conduit 17, and on this lug is pivotally mounted a pawl 20, adapted to pass through an opening in the rear side of the sleeve 12 and engage with the ratchet bar 14, as shown in Fig. 5.

A jointed or flexible thrust member is guided and movable lengthwise in the conduit 17 around the turn or bend therein, and is connected or engaged at its front end with the lug 19. This thrust member may consist as shown, of rollers 22, connected in pairs by axles 23 and spacing links 24, articulated with the roller axles, as shown in Figs. 5, 6 and 7, the rollers and links being yieldingly held together by a spiral spring 105 25 connected at the ends with the axles of the end rollers and confined in grooves in the under sides of the links.

The axle of the rear end rollers 23 is extended and passes freely through horizontal 110

slots 27 in the sides of the extension 2. The projecting ends of the rear axle 23 are connected by rods 28 on opposite sides of the extension 2 with the lower ends of branch arms 29 of a forked lever, which is fulcrumed on studs 30 projecting from opposite sides of the hub 10 adjacent the rear end of said extension. The branch arms 29 of the lever, preferably made separate from each other, are bolted together above the hub 10, and form at their upper ends a socket for a handle or lever arm 31, as shown in Figs. 2 and 4. The handle arm 31 is pivotally and slidably connected with the upper ends 15 of the branch arms 29 by a pin 32, fastened at the ends in the branch arms and passing through a longitudinal slot in the handle arm, so that the handle arm may be withdrawn from the socket and folded down out 20 of the way on the swivel plate 15 of the lifting member, as shown in Fig. 3, when the jack is not in use.

A hook-shaped pawl 34, pivotally connected with the branch arms 29 above the extension 2, is adapted to engage with a ratchet segment 35 formed on or attached to the extension, to lock the hand lever and hold the lifting member with a load resting thereon, in an elevated position, as shown in Fig. 1. The ratchet segment is provided with a lug or shoulder 37, with which the pawl 34 engages to lock and hold the fork arms 29 of the lever in an upright position when the handle arm 31 is withdrawn from the socket at their upper ends and turned down, as shown in Fig. 3.

A spring 38 connecting the pawl 34 with one of the branch arms 29, tends to hold the pawl in engagement with the ratchet segment 35.

The arm 31 is provided adjacent its outer end with a transverse handle bar 39 and with a sleeve or collar 40, slidably mounted thereon and connected by a jointed rod 41 with the pawl 34. The joint in the rod 41 is in approximate alignment with the pivot pin 32 of the handle arm, and the section of the rod which is connected with the sleeve 40 is guided on the handle arm adjacent to 45 the joint in the rod, as shown in Figs. 2, 3 and 4. The sleeve 40 is provided with a handle or grip 42, adjacent to and parallel with the handle bar 39.

To enable the operator to quickly raise 55 the lifting member to the starting point in engagement with a load preparatory to lifting the same with the handle arm 31 of the main operating lever, the jack is provided with a foot lever 44, fulcrumed on one of the 60 studs 30 and extending normally alongside the extension 2 to the lower part of the standard 1, where it is held in place and guided by a vertical keeper 45, formed on or attached to one side of the standard, as 65 shown in Figs. 1, 6 and 7. The ratchet bar

14 is provided with a pin or stud 47, projecting laterally therefrom through vertical slots in the sleeve 12 and standard 1 above the adjacent end of the lever 44.

To disengage the pawl 20 from the ratchet bar 12 for releasing the ratchet bar and permitting it to descend in the sleeve 12 to its lowest or normal position, therein, as shown in Figs. 3 and 5, the pawl is provided with a pin or stud 49, projecting laterally therefrom through a vertical slot 50 formed in the adjacent side of the standard, as shown in Fig. 3. This slot is formed with an enlargement at its lower end to permit the disengagement of the pawl 20 from the ratchet bar 14 only when the sleeve 12 is in its lowest position, as shown in Fig. 5, the pawl being held in engagement with the ratchet bar and preventing accidental release of the load by the engagement of the pin or stud 49 with 85 the rear side of the slot when the sleeve is elevated.

To facilitate disengagement of the pawl 20 from the ratchet bar when the sleeve 12 has been lowered with the load, a lever 52, 90 pivotally mounted on one side of the standard 1 and extending at its upper end above the lower end of the slot 50, is connected at its lower end by a rod 53 with an angular foot lever 54, pivotally mounted on the 95 extension 2 adjacent its rear end. A spring 55, connecting the lever 52 above its fulcrum with the bracket 6, holds said lever normally against a stop 56, with its upper end in front of the lower end of the slot 50 and out of 100 the path of the pin 49, as shown in Fig. 3.

In the operation of the jack, as in lifting a vehicle for example, the standard 1 being brought into position underneath the part of the vehicle to be engaged by the lifting 105 member, and the extension 2 carrying the operating levers being directed outwardly from the vehicle into a clear space, the ratchet bar 12 is elevated to the starting point, bringing the bearing plate 15 into 110 engagement with the vehicle by depressing the pedal of the foot lever 44, which operates directly on the ratchet bar by engagement with the pin 47, the ratchet bar being engaged and held in its elevated starting 115 position by the pawl 20. The handle arm 31 being turned up into alignment with the branch arms 29 and thrust into engagement with the socket between them, as shown in Figs. 1, 2 and 4, and unlocked by withdrawing the pawl 34 from engagement with the lug 37, is turned outward and downward, to or toward the position in which it is shown in Figs. 1 and 2, thereby operating through the connecting rods 28 and flexible 120 thrust member 22-23-24, against the lug 19 on the sleeve 12, to raise the sleeve with the lifting member 14-15 and lift the load resting on the bearing plate 15. The lifting member with the load, is locked and held 130

in elevated position by engagement of the pawl 34 with a tooth of the ratchet segment 35.

The extension 2, with the operating levers 5 and connections carried thereon, may then be swung on the caster wheel 8 and truck wheels 4, underneath the vehicle out of the way, the bearing plate 15 swiveling on the ratchet bar 14. The extension 2 and the connections between the operating levers and the lifting member being located close to the floor, will pass underneath a wheel or wheels of the vehicle when it is elevated but a short distance from the floor.

15 To lower the load and remove the jack therefrom, the extension 2 is swung outwardly into clear position, the pawl 34 is withdrawn from engagement with the ratchet segment 35 by the operator drawing 20 the handle 42 toward the handle bar 39, and the load is lowered with the lifting member and sleeve, under control of the lever arm 31 held by the operator. When the sleeve 12 reaches its initial position, as shown in Figs. 25 3, 5 and 6, thereby returning the lifting member to the starting point and relieving it of the load, which then rests on the floor, the pawl 20 is thrown out of engagement 30 with the ratchet bar 14 by depressing the foot lever 24, and the lifting member then drops in the sleeve 12 into its lowest position, the lever arm 31 being turned into an upright position. The lever arm 31 may then be withdrawn from the socket in the 35 branch arms 29 and folded down out of the way on the bearing plate 15, as shown in Fig. 3, the branch arms 29 of the lever being locked and held in an upright position by engagement of the hooked pawl 34 with the 40 lug 37.

Various changes in the details of construction and arrangement of parts may be made without departure from the principle and scope of the invention as defined in the following claims.

I claim:

1. In a lifting jack the combination of a standard having an elbow-shaped conduit, a lifting member guided in the standard adjacent to and parallel with a part of said conduit, a thrust member guided and movable lengthwise in said conduit, means for releasably connecting the thrust member with the lifting member, and means for applying pressure to the thrust member to operate the lifting member.

2. In a lifting jack the combination of a standard having an elbow-shaped conduit, a lifting member guided in the standard adjacent to and parallel with a part of said conduit, a flexibly jointed thrust member guided and movable lengthwise in said conduit, means for adjustably connecting one end of the thrust member with the lifting member, and means for manually exerting

pressure on the other end of the thrust member to operate the lifting member.

3. In a lifting jack the combination of a standard having a guideway and an elbow-shaped conduit part of which is adjacent to and parallel with said guideway, a sleeve fitted and movable lengthwise in the guideway, a lifting member fitted and movable lengthwise in the sleeve, means for adjustably connecting the sleeve with the lifting member, a flexible jointed thrust member confined and movable lengthwise in said conduit and adapted to engage at one end with a part of said sleeve, and means for exerting pressure against the other end of the thrust member transversely to said guideway.

4. In a lifting jack the combination of a standard having a lateral extension at its lower end forming with the standard an elbow-shaped conduit having an upright portion, a lifting member guided in the standard adjacent to and parallel with the upright portion of said conduit, a flexibly jointed thrust member guided in said conduit, means for releasably connecting one end of the thrust member with the lifting member, and a lever mounted on said extension and connected with the other end of the thrust member.

5. In a lifting jack the combination of a standard having an elbow-shaped conduit, a lifting member guided in the standard adjacent to and parallel with a part of said conduit, a flexible thrust member guided in said conduit and comprising rollers and spacing links, means for connecting the thrust member at one end with the lifting member, and means for exerting pressure on the other end transversely to the standard.

6. In a lifting jack the combination of a standard having a lateral extension forming therewith an elbow-shaped conduit, a lifting member guided in the standard parallel with a part of said conduit, a flexible thrust member guided and movable lengthwise in said conduit around the turn therein and comprising rollers connected in pairs by axles and spacing links between the axles, a spring connecting the end roller axles of the thrust member, means for connecting the thrust member at one end with the lifting member, and means for applying pressure to the other end of the thrust member toward and transversely to the standard.

7. In a lifting jack the combination of a standard formed with an elbow-shaped conduit, a sleeve guided in the standard parallel with a part of the conduit and provided with a lug projecting into the conduit, a ratchet bar guided in the sleeve, a pawl mounted on the sleeve for engaging and lifting the ratchet bar, a flexible thrust member guided and movable lengthwise in said conduit around the turn therein and adapted

- to engage at one end with the lug on the sleeve, and means for applying pressure to the other end of the thrust member toward and transversely to the sleeve and ratchet bar.
8. In a lifting jack the combination of a standard formed in one side with a vertical slot having an enlargement adjacent its lower end, a sleeve guided and movable lengthwise in the standard, a ratchet bar guided and movable lengthwise in the sleeve, a pawl pivoted on the sleeve and provided with a pin working in the slot in the standard and adapted to hold the pawl in engagement with the ratchet bar except when the pin is lowered with the sleeve and pawl into a position opposite the enlargement of the slot, means for quickly raising the ratchet bar in the sleeve, and means for raising and lowering the sleeve with the ratchet bar in the standard.
9. In a lifting jack the combination of a standard provided adjacent its lower end with a lateral extension forming therewith an elbow-shaped conduit having an upright part, a vertically movable lifting member guided in the standard parallel with the upright part of the conduit therein, a flexible thrust member guided and movable lengthwise in said conduit around the turn therein, means for connecting the thrust member at one end with the lifting member, a lever fulcrumed on said lateral extension and connected with the other end of the thrust member, and means for locking the lever for holding the lifting member at different elevations.
10. In a lifting jack the combination of a standard having a lateral extension forming therewith an elbow-shaped conduit having an upright part, a sleeve guided and movable lengthwise in the standard parallel with the upright part of the conduit therein, a lifting member guided and movable lengthwise in the sleeve, means for adjustably engaging the sleeve with the lifting
- member, a flexible thrust member guided and movable lengthwise in said conduit around the turn therein and engaging at one end with the sleeve, a lever mounted on said extension for quickly raising the lifting member in the sleeve to the load, and a lever mounted on said extension and connected with the other end of the thrust member for raising and lowering the sleeve with the lifting member and load relative to the standard.
11. In a lifting jack the combination of a standard having a lateral extension forming therewith an elbow-shaped conduit, a lifting member guided and movable in the standard adjacent to and parallel with the adjacent part of the conduit therein, a flexible thrust member guided and movable lengthwise in said conduit around the turn therein, means for connecting the lifting member with the adjacent end of the thrust member, and a jointed folding lever mounted on said extension and connected with the other end of the thrust member.
12. In a lifting jack the combination of a standard provided adjacent its lower end with truck wheels and with a horizontal extension forming with the standard an elbow-shaped guide conduit, a caster wheel connected with and adapted to support said extension adjacent the end opposite the standard, a lifting member guided and movable in the standard adjacent to and parallel with a portion of the guide conduit therein and provided at its upper end with a swiveled bearing, a flexible thrust member confined and movable lengthwise in said guide conduit around the turn therein, means for connecting the thrust member at one end with the lifting member, and means mounted on said extension for manually applying pressure to the other end of the thrust member.

In witness whereof I hereto affix my signature.

LAURENCE J. BERKELEY.
